ANTISTATIC DEVICE

Hughes Mouradian, Philadelphia, Pa.

Application January 22, 1940, Serial No. 314,960

23 Claims. (Cl. 250—10)

This invention relates to a radio transmission and receiving system and, more particularly, to the specific arrangements at both transmitting and receiving stations for the purpose of eliminating or reducing to a very low minimum "static" effects, as well as internally produced disturbances at the receiving station or stations.

There have lately been described in the art several effective methods of reducing static disturbances. These have been of several different types, using different instrumentalities for obtaining the desired results:

1. The use of multiple receiving antennas with volume and phase adjusting means for adding the signal impulses received and reducing the static impulses.
2. The use of a wide band of frequencies, in conjunction with frequency modulation, instead of amplitude modulation. Such a system has been described in a comprehensive manner by Prof. Armstrong in a paper published in I. R. E. Proceedings, May 1936, pages 689-740.
3. The use of two separate carrier frequencies for transmitting and receiving, each carrier frequency modulated in accordance with present practice and each including therefore, an upper and a lower side band, with the intensities of the two carriers themselves so phased as one of them to be at its maximum while the other is at its minimum. At the receiving end, the phases of the two carriers are again reversed.

The present disclosure differs from both of the above general methods described in sub-paragraphs 1 and 2, in that no multiple interconnected receiving sets are required, nor is it necessary to use a wide band of frequencies to obtain the desired effect. As well known, and as fully described by Armstrong, the use of a wide band of frequencies entails the use of very high frequency carrier, 40-150 megacycles, and precludes the utilization of the present day broadcasting range of frequencies. The frequency band required, with the high frequency carrier, is of the order of 200,000 cycles. This may be compared with the usual broadcasting band of 10,000 cycles to obtain an idea of the relative dimensional factors involved.

The method first disclosed in these specifications also differs from the arrangements described in sub-paragraph 3 in that special means are used to effectively suppress either the lower or the upper side band using, to effect this pur-

pose, double modulation at the transmitting end in conjunction with electric filters and is further carrier-suppressed throughout. Several variations have been disclosed at the transmitting end. In one variation single frequency carrier is used, in contrast with the double frequency method referred to in sub-paragraph 3. In a second variation where a double frequency transmitting system is used, both carriers are again suppressed thus enabling the use of adjacent carrier frequencies. This last feature further distinguishes the carrier-suppressed, single side band double frequency system of the present specifications from the arrangements previously disclosed by prior inventors. In all such prior arrangements, all using double frequency double side band transmission, a separation of the order of at least 15,000 cycles was required between the two fundamental frequencies of the double frequency system to avoid the carrier interference effect, or whistle.

A third variation which is also first disclosed in these specifications and is superimposed upon the first two variations consists in the "chopping" of the signal spectrum itself into a number of adjacent "pairs" of frequencies. Each pair still being of the single side band type and also carrier suppressed. We thus have, in this third variation, a multi-frequency transmitting system which, as clearly and definitely proved in these specifications, has the advantage of still greater ranges in static interference reduction. All of these several transmitting systems have their corresponding counterparts in the various receiving systems designed to operate in cooperative relation with the transmitting systems disclosed.

The reduction of static interference and also of internal noise has been, as well known, a prime preoccupation of the radio engineer. Except in the field of frequency modulation the improvements obtained in static reduction have been comparatively small even with multiple receiving antenna systems, i. e. of the order of 6-9 db., where the frequencies involved are in the broadcasting or low frequency range. Probable reductions in static of the order of 40 decibels and over have been shown as effectively obtainable in the attached specifications with the arrangements herein disclosed.

It is necessary in order to get a bird's eye view of the problems involved and of the importance of the novel solutions first disclosed in these specifications to bear in mind several well-established facts. First, that the total interference effect is directly proportional to the total width

of the band of frequencies allowed to enter the receiving equipment. For instance, where in order to receive both side bands, as in the systems broadly referred in sub-paragraph 3, the receiving equipment must be designed to receive a band twice as large, the "noise power" is four times as large. The second point to be borne in mind is that in all systems which depend for their functional operation upon two interference waves mutually reacting against each other the effectiveness of the reaction depends upon the frequency separation between the two interference waves. The relative effectiveness is inversely proportional to the separation in absolute frequency between the two static waves which are being made to interfere. In the case of the systems disclosed under sub-paragraph 3, this separation between the interfering waves is given by $2s+S$, where

s =side band width of the signal spectrum.
 S =Separation in frequency between the two carriers of the double frequency system.

In the case of the present system, as first disclosed in these specifications, the corresponding frequency separation is just s , instead of $(2s+S)$ as in the case of systems previously disclosed. In view of the general considerations briefly outlined hereinabove, which affect the primary purpose of the invention, a second most important advantage of the systems first disclosed in these specifications will be immediately apparent, i. e., the number of usable radio signalling channels will be several times greater with the systems herein disclosed than with similar systems heretofore disclosed. No changes in the number of radio signalling channels allocated by the Federal Communications Commission would be required, if all radio channels made use of the systems herein disclosed. A substantial reduction in the number of such radio channels of communication in use today would, on the contrary, have to be made if the similar systems, such as those described in sub-paragraph 3, were to be generally adopted.

A third, equally as great an advantage, of some of the receiving systems disclosed in these specifications consists in the possibility of using these systems for receiving directly the broadcasts from present day single frequency carrier, double side band broadcasting stations, without loss of the fundamental characteristic of static reduction. This is not possible with the systems described in sub-paragraph 3 hereinabove. In view of its importance, this point is reviewed in great detail with the description of the operational characteristics of the receiving system of Figure 3 and Figure 4 of the drawings.

This invention will be clearly understood from the following description, when read in connection with the attached drawings, of which Fig. 1 and Fig. 2 show the conventional type broadcasting equipment adapted for double carrier and double modulation as required by the invention; Fig. 3 and Fig. 4 show the conventional type receiving equipment adapted for double carrier and double demodulation; Fig. 5 indicates a variation of Fig. 1 of the drawings, which uses a single side band transmission; Fig. 6 indicates a variation of Fig. 3 of the drawings. Fig. 7 indicates a variation of Fig. 4 of the drawings; Fig. 8 indicates "static" disturbance neutralizing equipment to care for residual unbalances of equipment impedances and residual variations of intensity of static with absolute frequency.

No detail explanations are required for an understanding of the operation of the conventional type radio broadcasting equipment which terminates in terminals 1, 2 of Fig. 1 of the drawings. The essentially novel features of the arrangement consist in the use of two-step modulation for the purpose of separating the two side bands produced by modulation. The first step in the modulation is carried out at a sufficiently low frequency to enable this separation effectively and conveniently. The second step in the modulation, which is illustrated on Fig. 2 of the drawings, merely steps up the frequency to the frequency assigned for normal operation to the broadcasting station or point-to-point transmitting station. It will be noted that an essentially new feature of the arrangement consists in the use of carriers C_1 and C_2 , the frequency of carrier C_1 being

$$\frac{p_1}{2\pi}$$

cycles per second and the frequency of carrier C_2 being

$$\frac{p_2}{2\pi}$$

cycles per second. The numerical values of p_1 and p_2 are chosen so that

$$\frac{1}{2\pi}(p_2-p_1)$$

is equal to the band width of the speech or signal spectrum which it is desired to transmit. Thus, if the transmission of speech frequencies within the band 100 to 10,000 cycles (for the upper limit) is desired, then

$$\frac{p_2-p_1}{2\pi}=10,000 \text{ cycles}$$

The choice of p_1 and p_2 for the frequency factors of the respective carriers is made so that effective separation of the lower side bands can be made by means of filters from the upper side bands. At the present stage of the development of the art, such effective separation can be conveniently made, at frequencies as high as 60-80,000 cycles per second requiring, however, the use of crystal filters for the purpose. Band pass filter A of Fig. 1 of the drawings allows the free transmission of frequencies included between f_2 and $(f_2+10,000)$ cycles, thus suppressing the lower side band. Correspondingly, band pass filter B allows the free transmission of frequencies between $(f_1+10,000)$ and f_1 cycles, again eliminating the lower side band. The upper side band emerging from terminals 1, 2 will be proportional to $kCS \cos \{(p_2+q)t+\theta\}$ and the corresponding upper side band emerging from terminals 5, 6 will be proportional to $kCS \cos \{(p_1+q)t+\theta\}$ where—

k =coefficient of proportionality

C =common amplitude of carriers C_1 and C_2

q =common phase angles of carriers C_1 and C_2

S =amplitude of signal

An important feature of the invention is the transposition or phase reversal introduced between terminals 1, 2 and 3, 4 of Fig. 1 of the drawings. The total current reaching the terminals 7, 8 is proportional, therefore, to—

$$(1) -kCS \cos \{(p_2+q)t+\theta\} + kCS \{(p_1+q)t+\theta\}$$

To recapitulate, the important points involved are the use of the upper side bands only and the reversal in phase of one of the side bands. Evi-

dently equivalent results would be obtained, as will be seen later, if a transposition had been cut in between terminals 5, 6 and 7, 8 instead of between 1, 2 and 3, 4. It will also be evident that instead of the two upper side bands of carriers C_1 and C_2 , the two lower side bands could have been chosen, with the complete exclusion of these upper side bands.

Attention is here called to the fact that the total width of the frequency spectrum utilized is no greater, with the arrangement shown on Fig. 1 and Fig. 2 of the drawings than with the present day arrangements of double side band broadcasting. Furthermore, nothing in this invention restricts the total band width to twice 10,000 cycles. It could be anything desired for ordinary broadcasting purposes and it could be, say, 2,000,000 cycles wide if broadcasting television impulses. The descriptions given in the specifications and the arrangement of the drawings have been restricted, for purposes of convenience, to conventional broadcasting or point-to-point speech communication circuits.

Terminals 7, 8 of Fig. 2 of the drawings connect to terminals 1, 8 of Fig. 1 of the drawings. The purpose of the arrangement shown on Fig. 2 of the drawings is to step up the frequencies of the two side bands by f_0 cycles to the normal frequency $(f_2 + f_0)$ assigned to the broadcasting station. This is carried out through the use of amplifier C (optional), followed by the second modulator D, with carrier C_3 supplying current at frequency f_0 . Since the wave expressed by Equation 1 has two terms, the second modulating step produces four main waves (omitting from consideration the higher harmonics which are eliminated by low-pass filter E_2). We can, if we so choose, select again the upper side bands of the second modulator D. This is carried out by means of the high pass filter E_1 of the drawings, which allows the free transmission of all frequencies above $(f_1 + f_0)$ cycles and virtually eliminates all frequencies below $(f_1 + f_0)$ cycles. The equation of the wave radiated by the transmitting antenna of Fig. 2 of the drawings is given by Formula 2, below.

$$(2) \quad -k'CC_3S \cos \{(p_2 + p_0 + q)t + \theta_1\} \\ +k'CC_3S \cos \{(p_1 + p_0 + q)t + \theta_1\}$$

It will be noted that the transmitting system above described is carrier suppressed throughout, since the radiated wave as given by Formula 2 does not contain the carrier itself, but only two (upper) side bands. The suppression of the intermediate carrier is obtained on Figure 1 of the drawings by the symmetrical feed of the carrier supply through the midpoint of a choke coil in the input circuit of the modulator, and the mid-point of the output transformer of the modulator.

The suppression of the final carrier of frequency $(f_1 + f_0)$ is obtained by the action of the high pass filter E, which allows only the flow of currents exceeding $(f_1 + f_0)$ cycles in frequency. In any transmitting system which operates on a double carrier basis, it is impossible, of course, to avoid the beat note or whistle between the carriers, unless these two are separated in frequency by 15,000 or 20,000 cycles so as to render said beat note inaudible. In the absence of a system suppressing the carrier, therefore, the frequency spectrum used by any double frequency transmitter would include twice the side band frequency plus the 15,000 cycles or so required to avoid the beat note. If the radio transmission

system is restricted by regulation to a 5 kilocycle width for each side band, then the frequency spectrum required would be 25,000 cycles wide. In the case of the transmitting system described in the specification and as shown on Fig. 1 and Fig. 2 of the drawings, where this system is applied for regular radio broadcasting purposes, the frequency spectrum required is only 10,000 cycles wide. This is due to the fact that only the upper side bands are allowed through (by the action of filters A and B of Fig. 1 of the drawings) and these being adjacent in frequency, the entire width of the spectrum required is twice the side band width of 5 kilocycles or just 10 kilocycles wide. This is of tremendous practical importance, since should the broadcasting companies see fit to make the changes required by Fig. 1 and Fig. 2 of the drawings, it would be possible to operate all present day broadcasting stations without mutual interference, but with greatly reduced static. The transmitting system described in the present specifications results therefore in maximum economy in the use of the ether.

Figure 3 and Figure 4 taken together show the arrangement required at the receiving end. The equipment shown on Fig. 3 of the drawings includes, in addition to the receiving antenna, the usual radio-frequency amplifier F and the intermediate frequency modulator G, followed by band pass filters H and J. Evidently, except where point-to-point transmission is involved, the modulator G must be supplied with means for varying the frequency f_0 of the intermediate carrier. After demodulation, the resultant waves are passed through filters H and J, which select the lower side bands in each case. The main waves involved have the frequency factors $(p_2 + q)$, $(p_1 + q)$, $(2p_0 + p_2 + q)$. The band pass filter H is designed for a free transmission band included between the frequencies of f_2 and $(f_2 + 10,000)$ cycles, while band pass filter J is designed for the band f_1 and $(f_1 + 10,000)$ cycles. As stated hereinabove, the free transmission band width of 10,000 cycles may be anything determined upon in advance. The wave reaching terminals 13, 14 will be given by—

$$-lCC_3C_4S \cos \{(p_2 + q)t + \theta_2\}$$

The wave reaching terminals 17, 18 will be given by—

$$+lCC_3C_4S \cos \{(p_1 + q)t + \theta_2\}$$

where—

l =coefficient of proportionality

C_4 =amplitude of carrier supplied to demodulator G

θ_2 =phase difference

We may note, now, that a transposition has been inserted in the upper side band between terminals 13, 14 and 15, 16. The result of this transposition is to change the sign of this upper side band so that this side band wave, when it reaches terminals 15, 16 has the expression—

$$+lCC_3C_4S \cos \{(p_2 + q)t + \theta_2\}$$

The equipment shown on Fig. 4 of the drawings completes the process of demodulation. The upper side band $(p_2 + q)$ is amplified by intermediate frequency amplifier K_1 , if amplification is necessary, and further demodulated by demodulator L_1 , which is supplied by carrier C' at a fixed frequency f_2 . The lower side band $(p_1 + q)$ undergoes the same treatment through amplifier K_2 and demodulator L_2 , which is supplied by carrier

C' at a fixed frequency f_1 . The final result of the demodulation process illustrated on Fig. 4 of the drawings is a speech wave which is given by the expression—

$$(3) \quad 2l'CC_3C_4C'S \cos(qt+\theta_3)$$

where—

l' =coefficient of proportionality

C' =common amplitude of carriers of frequency f_1 and f_2 supplied to demodulators L and N

We will now consider what effect the arrangement shown on Fig. 3 and Fig. 4 of the drawings has upon the "static" disturbances collected by the receiving antenna or produced by the receiving equipment (thermal agitation in antenna circuit, the grid circuit of the radio frequency amplifier, shot effects, etc., in all parts of the receiving circuit preceding band pass filters H and J). We will designate the amplitude of a single disturbing sinusoidal wave in the frequency range $(f_0+f_2+10,000)$ by N_a and the corresponding amplitude of a single disturbing wave in the frequency range $(f_0+f_1+10,000)$ by N_b . The corresponding phase differences will be indicated by (φ_a) and (φ_b) . The actual frequencies of the two disturbances N_a and N_b will be designated by $(f_0+f_2+f_n)$ and $(f_0+f_1+f_n)$. With the above assumptions, the total "disturbance" will therefore be designated by the summations—

$$\Sigma N_a \cos \{(p_0+p_2+p_n)t+\varphi_a\} + \Sigma N_b \cos \{(p_0+p_1+p_n)t+\varphi_b\}$$

The values of f_n will vary only between 0 and 10,000 (or whatever band width other than 10,000 cycles might have been preselected for the band of useful signals), since all frequencies outside this range are eliminated by the filters included in the radio receiving circuit of Fig. 3 and Fig. 4 of the drawings. Considering the disturbance waves in pairs, as already suggested, as

$$N_a \cos \{(p_0+p_2+p_n)t+\varphi_a\}$$

and

$$N_b \cos \{(p_0+p_1+p_n)t+\varphi_b\}$$

the frequencies of these two waves are stepped down by f_0 cycles through the action of the demodulator G , and their respective amplitudes and phases become—

$$mN_bC_4 \cos \{(p_1+p_n)t+\varphi_b\}$$

and

$$mN_aC_4 \cos \{(p_2+p_n)t+\varphi_a\}$$

where—

m =coefficient of proportionality

C_4 =amplitude of carrier C_4 of frequency f_0

The above two individual disturbance waves are transmitted through, by band pass filters H and J , respectively. The addition waves or upper side bands having the frequencies $(2f_0+f_2+f_n)$ and $(2f_0+f_1+f_n)$ are eliminated by these same filters. In view of the effect of the transposition inserted between terminals 13, 14 and 15, 16 of Fig. 3 of the drawings, the two disturbance waves reaching terminals 15, 16 and 17, 18 of Fig. 4 of the drawings will be expressed by:

$$(a) \quad -mN_aC_4 \cos \{(p_2+p_n)t+\varphi_a\}$$

$$(b) \quad +mN_bC_4 \cos \{(p_1+p_n)t+\varphi_b\}$$

After transmission through elements K_1 , L_1 and the low pass filter M of Fig. 4 of the draw-

ings, the expressions for waves a and b will become—

$$(a) \quad -m'N_aC_4C' \cos(p_n t + \varphi_a'') \\ (b) \quad +m'N_bC_4C' \cos(p_n t + \varphi_b'')$$

where—

m' =coefficient of proportionality

C' =common amplitude of carriers supplied to demodulators L_1 and L_2 .

The total disturbance in the loud speaking equipment will then be expressed by—

$$(4) \quad \text{Disturbance} = m' \Sigma N_a C_4 C' \cos(p_n t + \varphi_a'') + m' \Sigma N_b C_4 C' \cos(p_n t + \varphi_b'')$$

The summation signs include all frequencies f_n between 0 and 10,000 cycles.

It will be clear by inspection of the expression for the "noise," as given by Formula 4, that the disturbing effect of such noise has now two terms which are in opposition of phase, instead of being directly additive as they are with present day arrangements where both side bands, the so-called upper and lower sides of a single modulation step, are transmitted. Incidentally, the two-side band transmission of Fig. 1, Fig. 2, Fig. 3 and Fig. 4 of the drawings should not be confused with the double side band transmission of the present art. The important difference, outside of the physical separation of the side bands required by the present invention, is that the phase differences of the twin side bands of the present art are of opposite sign, i. e., $+\theta$ and $-\theta$, while they are of the same sign in the present invention. This point is extremely critical in the final elimination of "noise" from the useful speech or signal impulses.

If the "noise" disturbances, as usually assumed in present day practice, include frequencies in the whole spectrum $(f_0+f_2+10,000)$ and (f_0+f_1) and are substantially uniform in amplitude N' and phase difference φ , then Summation 4 is given:

$$(5) \quad \Sigma m' N C_4 C' \{ \cos(p_n t + \varphi'') - \cos(p_n t + \varphi'') \} = 0$$

This is the ideal condition, where "noise" has been completely eliminated, and represents the best possible result that can be obtained.

Considering the above situation from a broader standpoint, the "noise" effect when considered in pairs of frequencies, each separated by f_n cycles from its respective carrier frequencies (f_0+f_2) and (f_0+f_1) cycles, can be written in the form—

$$(5) \quad m' C_4 C' \{ (N_b \cos \varphi_b'' - N_a \cos \varphi_a'') \} \cos p_n t - (N_b \sin \varphi_b'' - N_a \sin \varphi_a'') \sin p_n t$$

Suppose we designate—

$$(6) \quad N_b \sin \varphi_b'' - N_a \sin \varphi_a'' \text{ by } N \sin X$$

$$(7) \quad N_b \cos \varphi_b'' - N_a \cos \varphi_a'' \text{ by } N \cos X$$

Bearing in mind (6) and (7), we can rewrite Equation 4 in the more compact form:

$$(8) \quad \text{Static disturbance} = m' N C_4 C' \Sigma \cos(p_n t + X)$$

where—

$$(9) \quad N^2 = N_a^2 - 2N_a N_b \cos(\varphi_a'' - \varphi_b'') + N_b^2$$

$$(10) \quad \text{tg } X = \frac{N_a \sin \varphi_a'' - N_b \sin \varphi_b''}{N_a \cos \varphi_a'' - N_b \cos \varphi_b''}$$

The total "noise power," as so called and as given by $(m' C_4 C')^2 N^2 \cos^2(p_n t + X)$ is thus the summation of all terms similar to N^2 for all frequencies included in the band 0 to 10,000

cycles per second. Where the phase difference $(\phi_a'' - \phi_b'')$ is substantially equal to zero, the noise power for frequency f_n is practically equal to

$$\frac{1}{2}(N_b - N_a)^2$$

A drastic reduction in noise power and, in favorable cases, an actual obliteration of noise, is the result of the arrangement first described in these specifications.

The following discussion will give a closer insight into the meaning and limitations of Equation 8 for noise disturbance.

It may be noted that while N_b or N_a and ϕ_b'' or ϕ_a'' are extremely variable, their differences are not random but are closely interrelated. Static disturbances, as well known, are due to electric discharges taking place at more or less distant points, each such disturbance being best represented by recurring very short period impulses. Where, for instance, a short period impulse has a square wave form, it can be represented by a Fourier series consisting of a fundamental and an infinite array of harmonics. The amplitudes N of these harmonics are, as well known, inversely proportional to their frequencies. The part of this impulse spectrum that is received on a radio receiver is a small band of the very high order of harmonics. Since the frequency difference between the highest and lowest frequencies is small compared to the mid-frequency of the band, all of the frequencies received are of practically equal amplitude N . These harmonics are, furthermore, so related to each other by virtue of their relation to a common fundamental frequency that they are all in phase at the instant the impulse starts or stops. Since the source of the static, however, is usually at quite some distance there will be, in addition to the small variations with frequency of noise intensity N , additional variations brought about by the variation with frequency of the attenuation of the waves between the point where the impulse originated and the receiving station. For instance, if the source of disturbance is at a distance of 500 kilometers from the receiving stations, the difference in intensity of the received ground waves (for 1 k.w. radiated power) for 500 kilocycles and 1000 kilocycles is as follows:

Microvolts per meter

500 kilocycles	20
1000 kilocycles	0.9

(See International Radio Consulting Committee Report on "Radio Wave Propagation," I. R. E. Proceedings, Oct. 1938, page 1196, Fig. 2.) By interpolation we find, for the corresponding intensity at 750 kilocycles, 5 microvolts per meter and, for a 10-kilocycle frequency change from 750 kilocycles, a change of 5.7%. Now, as to the probable variation at the source, as above stated, the relative variation would be, for the same 10 kilocycle change of frequency, around a 750 kilocycle carrier:

Intensity change—

$$10 \text{ kilocycles} - \frac{10}{750} = 0.013$$

The above two variations are cumulative since the intensity of the higher harmonic is smaller by 1.3% and the relative attenuation greater by 5.7%; hence a total change of 7%. It will be noted that, for the sky waves, no distinction as to variation in intensity with frequency is being

made (see page 1198, Fig. 4, I. R. E. Proceedings). It would seem proper to conclude, in view of the fact that static disturbances will utilize sky transmission as well as ground transmission, that the variation in intensity for a change in frequency of 10 kilocycles will be less than 7%. If, instead of 500 kilometers, we had assumed that the source of static disturbance was 1000 kilometers, or even a greater distance away from the receiving station, then the ground wave would be negligibly small, the sky wave would be definitely dominating and, as shown above, no material change in amplitude is noted for sky waves in the radio art today for all frequencies designated as "medium frequencies" in the Report of the International Radio Consulting Committee (C. C. I. R.) referred to hereinabove. It is therefore not unreasonable to assume that if we take 10% as the possible maximum difference in intensity between frequencies 10 kilocycles apart at any given instant of time, for a broadcasting or transmitting carrier frequency, due to a single source of disturbance, we will not be too far from the truth. In fact, the figure just indicated is really a high maximum when considering the receiving conditions for the present day broadcasting range of frequencies. In this case, if the source of static is located 500 miles from the receiving station, the sky wave will dominate over the direct transmission wave by a ratio of 50 to 1. Since for the sky wave no change in attenuation need be expected (see Fig. 5, Committee Report on Wave Propagation, page 1199, I. R. E. Proceedings, October, 1938), we need not consider any difference in amplitude between frequencies 10,000 cycles apart due to this cause. The source of static has to be not more than 100-125 miles before differences of attenuation factors need actually be considered. For a distance as short as this, as just indicated, the percentage change in attenuation for a difference of 10,000 cycles will be about 2.5% around 750 kilocycles and the total change 3.8%. This last figure means that the improvement shown in Formula 11 can be exceeded by 6 db. As to the effect of distance upon phase differences, such phase difference between two different harmonics 10 kilocycles apart, would be brought about, if the velocity of transmission of two radio waves 10 kilocycles apart in frequency, would be substantially different. None apparently has been noted in the art. If there had been any appreciable difference, such difference would have resulted in the distortion of speech waves. None, at least so far, has been noted. In view of the facts just noted, the relative "noise power" with the arrangement herein first described, as compared with the corresponding "noise power" with present-day double side band transmission is given by the ratio—

$$\frac{(N_b - N_a)^2}{(N_b + N_a)^2} = \frac{(0.9 - 1.0)^2}{(0.9 + 1.0)^2} = \frac{.01}{3.61} = 0.00277$$

The above ratio means a reduction in "noise" power expressed in decibels equal to—

$$(11) \quad 10 \log_{10} 361 = 10 \times 2.57 = 25.7 \text{ db.}$$

If instead of the arrangement first disclosed in the present specification, the usual single carrier double side band method of demodulation had been used at the receiving station, and one of the side bands were also reversed, the equations of the resulting disturbance waves would still be given by Formulas 4 to 9 inclusive, with the exception that the sign of the phase difference of

the component N_b is now $-\varphi''b$ instead of $+\varphi''b$, assuming N_b is of the lower side band type and N_a is of the upper side band type. Equation 9, for the present case would become

$$(9a) \quad N^2 = N_a^2 - N_a N_b \cos(\varphi_a'' + \varphi_b'') + N_b^2$$

Even if we had the ideal situation which, with the arrangement of the present specifications, results in $N=0$ as already shown, we would obtain for the single carrier double side band arrangement with one side band reversed of Formula 9a, a probable average given by the law of random variations.

$$(9b) \quad N^2 \text{ (average)} = 2N_a^2 \frac{\sqrt{3}}{2}$$

The law of random variations is applied here since the phase φ'' of the disturbance wave is absolutely uncontrollable and will have random values distributed between 0 and 2π and $\cos(\varphi_a'' + \varphi_b'')$ will take values varying between 0 and ± 1 .

The fundamental importance of the use of two carriers with two retained side bands of the same type (after elimination of the opposite side bands) is thus made evident as a static, as well as internal disturbance, eliminating device. It is therefore broadly claimed as a fundamental conception.

The transmitting arrangement, as shown on Fig. 1 and Fig. 2 of the drawings, uses two side bands (both upper or lower) with two modulating carriers. This arrangement utilizes the same frequency spectrum as the present day double side band arrangements. It is not strictly necessary, however, for the purposes of the present invention, to use two side bands at the transmitting station. The use of a single side band would be sufficient, thus realizing economies in equipment costs and making it possible to use additional transmitting or broadcasting station call assignments by the Federal Communications Commission. Such an arrangement is described on Fig. 5 of the drawings. It is essentially the same system as shown on Fig. 1 of the drawings, except that modulation is carried out at a single carrier frequency, instead of two different frequencies separated by the width of the signal spectrum as in Fig. 1. It will be recalled that the receiving equipment uses, for the second step of modulation, the two carrier frequencies f_1 and f_2 , which latter frequency exceeds f_1 by the width of the signal spectrum. The carrier frequency of Fig. 5 of the drawings can be either f_1 or f_2 . In what follows, it is assumed that the carrier frequency of the first modulator, i. e., the modulator associated with Fig. 5 of the drawings, is f_2 cycles. Where the final radiated carrier frequency is quite low, as it is for instance with the long wave Transatlantic telephone circuits, the two steps in the modulation process can be merged into a single step, with resulting greater economies in installation. In general, however, the two step modulation process is indicated in view of the need for effectively separating the two side band waves from each other, eliminating one through the action of band pass filter A and radiating the other. Let us assume that filter A has the free transmission band f_2 to $(f_2+10,000)$ cycles for purposes of convenient exposition of the subject. Under these conditions, the wave reaching common terminals 7, 8 of Fig. 5 and Fig. 2 of the drawings is given by—

$$(12) \quad kCS \cos \{(p_2+q)t+\theta\}$$

The wave given by Formula 12 is amplified by the intermediate amplifier (optional, depending upon the amount of amplification required) and is next stepped up in frequency by modulator D by f_0 cycles. Only the upper side band of the main products of modulation is allowed to get through by high pass filter E₁ and the expression of the wave radiated by the transmitting antenna is given by—

$$(13) \quad k'CC_3S \cos \{(p_2+p_0+q)t+\theta'\}$$

No changes will be required with the above described single side band system, in the receiving equipment of Fig. 3 and Fig. 4 of the drawings. If, now, the demodulating process is carried at frequency f_0 , the resulting side band wave which is allowed to pass by filter H, will be given by—

$$(14) \quad lCC_3C_4S \cos \{(p_2+q)t+\theta_2\}$$

All of the useful speech frequencies are, in this case, included in the band f_2 and $(f_2+10,000)$ cycles. Hence, there will be no speech currents flowing through filter J. After further amplification by element K₁ of Fig. 4 and a second demodulation by element L₁, the final speech spectrum reaching the loud speaker will be given by—

$$(15) \quad -l'CC_3C_4C'S \cos (qt+\theta_3)$$

The negative sign has been used in view of the phase reversal introduced between terminals 13, 14 and 15, 16 of Fig. 3 of the drawings. This sign reversal is of no practical significance since we are dealing with a single speech wave and all components are affected alike.

Since no changes were introduced in the arrangement of Fig. 3 and Fig. 4 of the drawings, the reception of "static" and certain other internal disturbances will remain exactly as previously described. Hence, the amplitude of these disturbances is still given by the two equivalent summations, Formulas 4 and 8.

It will be noted that with the system just described, the ratio of signal power to "noise" power is only

$$\frac{1}{4}$$

or 6 db. less, than with the arrangement using two side bands shown on Fig. 1 and Fig. 2 of the drawings. This will be clearly evident by comparing Formulas 14 and 3.

In view of the large investment already incurred in the broadcasting and transmitting stations which are designed to operate on the familiar double side band arrangement of the present art, the question arises whether the receiving system first described in these specifications can be used to advantage in conjunction with these stations.

There appears to be no way of using both side bands of the double side band arrangement of the present art and still retain the static disturbance reduction feature of the present invention.

I find, however, that it is possible to "block off" one side band and use the other in the manner described below and still obtain the same advantages as can be secured by the use of Fig. 5 and Fig. 2 of the drawings as a transmitting arrangement, with Fig. 3 and Fig. 4 of the drawings as a receiving arrangement.

The wave radiated by the transmitting an-

enna is given, for the standard double side band arrangement of today, by—

$$(16) \quad C \cos pt + kCS \cos \{(p+q)t + \theta\} \\ kCS \cos \{(p-q)t - \theta\}$$

where

p =frequency factor of carrier C

C=amplitude of carrier radiated by transmitting antenna.

Assume, now, that this Wave 16 is received by the equipment shown on Fig. 3 of the drawings with the frequency of the oscillator associated with the demodulator G so adjusted that

$$(17) \quad p_0 = p - p_1$$

The resulting demodulated wave is given by—

$$(18) \quad k_1'CC_4 \cos \{pt + \theta_1\} + \\ k'CC_4S \cos \{(p_1+q)t + \theta + \theta_1\} + \\ k'CC_4S \cos \{(p_1-q)t - \theta + \theta_1\}$$

where—

$C_4 \cos \{(p-p_1)t - \theta_1\}$ —carrier supplied by element G.

The first term and the second term are passed freely by band pass filter J, which has the cutoff frequencies f_1 and $(f_1+10,000)$ cycles per second.

The third term, which represents the "image" of the side band wave given by the second term of Formula 18 is "blocked off" completely since it includes components which individually have frequencies lower than the lower cutoff point of filter J and, obviously, also lower than the lower cutoff point of filter H.

The speech wave which reaches the loud speaking equipment, after amplification by element K_2 and demodulation by element L_2 , is given by—

$$(19) \quad -l'CC_4C'S \cos \{qt + \theta_3\}$$

The first term in Wave 18, after the second demodulation by element L_2 , results in a direct current component and remains in the plate current of the demodulator L_2 .

The reception, amplification, demodulation, etc., of static and internal noise disturbances follow exactly the same path and pattern as heretofore described. The signal to noise ratio is therefore the same as indicated for the single side band transmitting system of Fig. 5 and Fig. 2 of the drawings in conjunction with the receiving system of Fig. 3 and Fig. 4.

There is a second setting of the intermediate frequency oscillator which can be used, still by the "blocking out" procedure provided, further, additional equipment to that shown on Fig. 3 and Fig. 4 of the drawings is supplied. The equipment referred to would consist of a third demodulator and a second low pass filter admitting frequencies between 0 and 10,000 cycles, which would be wired between element M and the audio amplifier equipment of Fig. 4 of the drawings. This third demodulator would be supplied by carrier C_5 at a frequency of 10,000 cycles. The second setting is that given by the equation—

$$(20) \quad p_0 = p - (p_2 + 2\pi 10,000)$$

The received wave, after demodulation by element G, is given by—

$$(21) \quad k_1'CC_4 \cos \{(p_2+W)t + \theta_1\} + \\ k'CC_4S \cos \{(p_2+W+q)t + \theta + \theta_1\} + \\ k'CC_4S \cos \{(p_2+W+q)t - \theta + \theta_1\}$$

where

$$W = 2\pi \times 10,000$$

The first and third terms will be passed freely by band pass filter H. The second term is "blocked out" since all its components have frequencies which are higher than the higher cutoff point of filter H and, obviously, also higher than the higher cutoff point of filter J.

The wave passed by filter H—after amplification and demodulation by elements K_1 and L_1 , respectively, is given by—

$$10 \quad (22) \quad -l_1'CC_4C' \cos \{Wt + \theta_2\} - \\ l'CC_4C'S \cos \{(W-q)t - \theta + \theta_2\}$$

It will be noted that the second term in Equation 22 represents an "inverted" speech wave.

15 Hence the need for the additional equipment referred to hereinabove to restore it to normal. When this wave is now transmitted through the third demodulator with carrier C_5 supplied at a frequency of

$$20 \quad \frac{1}{2\pi} \times W \text{ cycles per second}$$

the resultant is given by—

$$(23) \quad -l''CC_4C'C_5S \cos \{qt + \theta - \theta_3\}$$

25 where

l'' =coefficient of proportionality

The first term of Equation 22, when demodulated, results in a direct current component, which remains in the plate circuit of the third demodulator.

30 It remains to be shown that the static disturbance reduction feature has not been adversely affected.

35 The "noise" component, as given by Formula 8, when modified by the action of the third demodulator, will be given by—

(24) "Noise"—

$$40 \quad m''C_4C'C_5\Sigma N \cos \{(W-p_n)t + X + \theta_3\} \\ m''C_4C'C_5\Sigma N \cos \{(W-p_n)t - X - \theta_3\}$$

45 The first term in the above equation, including as it does components exceeding in frequency the higher cutoff point of the low pass filter having a free transmission band of

$$0 \text{ to } \frac{W}{2\pi} \text{ cycles}$$

50 is eliminated by said filter. The second term merely "transposes" or inverts a noise component of p_n cycles into a noise component of $(W-p_n)$ cycles at the same "equivalent" amplitude, so far as it is relative to the amplitude of the speech waves. This transposition is immaterial, for the reasons that have been fully described in conjunction with the analysis of the relatively small variation with frequency of the amplitude and phase of static disturbances within the band of frequencies received by Fig. 3 and Fig. 4 of the drawings.

55 The second setting of the oscillator of demodulator G, as given by Equation 20, does result in a system enjoying the benefits of static reduction, but it suffers under the handicap of requiring an additional demodulator and filter, with no offsetting advantages as compared with the first setting which is given by Equation 17. For this reason the electrical equipment arrangement for utilizing this second setting, in the manner described hereinabove, has not been illustrated on the drawings.

70 The two settings, as given respectively by Equations 17 and 20, have the frequencies $(F-f_1)$ and $(F-f_2-10,000)$ where F is the frequency of the

distant carrier. The difference between these two frequencies is $(f_2 + 10,000 - f_1)$, or 20,000 cycles, or twice the assumed width of one side band. When the frequency setting of the oscillator associated with demodulator G is intermediate between these two, i. e., if $p_0 - p - p_2$ or $f_0 - F - f_2$, both side bands are allowed to pass through by filters H and J, but these transmitted side bands are opposed in sign, on account of the transposition between terminals 13, 14 and 15, 16 of Fig. 3 of the drawings. Furthermore, subsequent demodulation by elements L₁ and L₂ results in "inverting" one of these side bands (the lower frequency side band). It is impracticable, as previously noted, to use both side bands of the double side band system of the present art in view of the points just mentioned.

Summarizing the preceding analysis, it may be stated that there is just a single setting of the frequency of the variable frequency oscillator of Fig. 3 of the drawings, which allows for the reception of one side band of the double side band system of the present art with resultant radical improvement in static disturbance reduction. While a great many different methods for obtaining this setting will be apparent to those versed in the art, perhaps the simplest operating method for the receiving set of Fig. 3 and Fig. 4 of the drawings, when used in conjunction with transmitting stations utilizing the double side band transmission of the present art, is to open the circuit at demodulator L₁ and vary the setting of the oscillator of demodulator G until the distant transmitting station is properly tuned in. When this setting has been obtained, in the simple manner just described, the circuit interruption at demodulator L₁ may then be restored and the full advantages of static disturbance reduction obtained.

Where it is necessary to obtain a greater reduction than that given by Formula 11, I find that such further reduction can be secured by using the following modifications in the transmitting and receiving arrangements previously described. The equipment arrangement at the transmitting station will still be given by Fig. 1 and Fig. 2 of the drawings, but the design of the apparatus will follow somewhat different lines. Carrier C₁ will be adjusted, as before, to deliver current at a frequency of f_1 cycles, but carrier C₂ will now be required to deliver current at $(f_1 + 2f)$ cycles, where f is the width in cycles of the speech or signal spectrum. Filters A and B will be designed as follows:

	Cutoff frequencies	
	Lower	Higher
Filter B	f_1	$f_1 + f$
Filter A	$f_1 + 2f$	$f_1 + 3f$

With these adjustments in mind, it will be evident that the wave leaving terminals 3, 4 of band filter A will be given by—

$$(25) \quad -kCS \cos \{(p_2 + q)t + \theta\}$$

The wave leaving band filter B will be given by—

$$(26) \quad +kCS \cos \{(p_1 + q)t + \theta\}$$

It will be noted that the fundamental difference between the double side band arrangement previously described and the present one is that the frequencies of the two carriers C₁ and C₂ are now separated by $2f$, or twice the free pass band widths of filters A and B. It should be remem-

bered that f , as before, represents the width of the signal or speech spectrum which it is desired to transmit. There will be no change required in Fig. 2 of the drawings. The wave radiated by the transmitting antenna is given by—

$$(27) \quad -k'CC_3S \cos \{(p_2 + p_0 + q)t + \theta_1\} \\ +k'CC_3S \cos \{(p_1 + p_0 + q)t + \theta_1\}$$

At the receiving end, the arrangement required is shown on Fig. 6 and Fig. 7 of the drawings, which replace Fig. 3 and Fig. 4, respectively. The received wave is amplified by radio frequency amplifier F and stepped down in frequency by demodulator G. The output of the element G of the drawings is wired to common bus-bars cc' to which are connected four band pass filters—H₁, H₂, J₁ and J₂, with the following cutoff points:

	Cutoff points	
	Lower	Higher
H ₁	$f_1 + 3f$	$f_1 + 4f$
H ₂	$f_1 + 2f$	$f_1 + 3f$
J ₁	$f_1 + f$	$f_1 + 2f$
J ₂	f_1	$f_1 + f$

There will evidently be no signal currents flowing through band pass filters H₁ and J₁, in view of the effect of filters A and B at the transmitting end. There will, however, be static disturbance and internal noise currents flowing through these band pass filters just mentioned, as well as through filters H₂ and J₂.

Considering first the effect upon the received signals of the circuit shown on Fig. 6, it may be noted that the output current of demodulator G is given by—

$$(28) \quad -l'CC_3C_4S \cos \{(p_2 + q)t + \theta_2\} \\ +l'CC_3C_4S \cos \{(p_1 + q)t + \theta_2\}$$

The signal current expressed by the first term in Equation 28 will follow through band pass filter H₂, the second term flowing through filter J₂. The first current amplified by element K₂ and demodulated by element L₂ of Fig. 7 of the drawings, will reach terminals 23, 24 and its amplitude will be given by—

$$(29) \quad -l'CC_3C_4C'S \cos (qt + \theta_3)$$

The current expressed by the second term of Formula 28 after amplification by element K₄ and demodulation by element L₄, will reach terminals 27, 28 with an amplitude given by—

$$(30) \quad l'CC_3C_4C'S \cos (qt + \theta_3)$$

In view of the transposition T₃ introduced between terminals 23, 24 and 25, 26, the final signal current reaching the audio or other low frequency signal equipment will be given by—

$$(31) \quad 2l'CC_3C_4C'S \cos (qt + \theta_3)$$

This is exactly the same equation as given by Formula 3. Thus the arrangement indicated on Fig. 6 and Fig. 7 of the drawings is as efficient as the arrangement previously disclosed on Fig. 3 and Fig. 4 of the drawings, when use is made of the same type of equipment.

The static disturbances received and internal disturbances originating in the equipments preceding the band filters of Fig. 6, are transmitted to terminals 15, 16—17, 18—19, 20 and 21, 22 through filters H₁, H₂, J₁ and J₂ in four distinct waves—

(a) Through filter H₁ to terminals 15—16

$$-mNaC_4 \cos \{(p_2 + p + p_n)t + \varphi_a\}$$

The negative sign is used in view of the transposition T_1' .

(b) Through filter H_2 to terminals 17-18

$$+mN_bC_4 \cos \{(p_2+p_n)t+\varphi_b'\}$$

(c) Through filter J_1 to terminals 19-20

$$-mN_cC_4 \cos \{(p_1+p_n)t+\varphi_c'\}$$

The negative sign is used in view of the transposition T_2' inserted between element G and the input circuit of filter J_1 .

(d) Through filter J_2 and terminals 21, 22

$$+mN_dC_4 \cos \{(p_1+p_n)t+\varphi_d'\}$$

The term p in all of the above expressions is equal to $2\pi f$.

After transmission through elements K_1 and L_1 of Fig. 7, and bearing in mind the transposition T_3 between terminals 23, 24 and 25, 26, the expression for the Wave a becomes—

$$+m'N_aC_4C' \cos (pnt+\varphi_a'')$$

Similarly, Wave b may be written as given by—

$$-m'N_bC_4C' \cos (pnt+\varphi_b'')$$

The corresponding expressions for Waves c and d will be given by—

$$-m'N_cC_4C' \cos (pnt+\varphi_c'')$$

$$m'N_dC_4C' \cos (pnt+\varphi_d'')$$

To obtain the full value of the static disturbances passed through the receiving circuit, we have to summate expressions of the type just written for a single component having the frequency f_n so as to include all components between 0 and f cycles, i. e., the entire signal spectrum. This summation is given by—

$$(32) m'C_4C' \Sigma \{N_a \cos (pnt+\varphi_a'')$$

$$-N_b \cos (pnt+\varphi_b'') - N_c \cos (pnt+\varphi_c'')$$

$$+N_d \cos (pnt+\varphi_d'')\}$$

The above expression can be readily reduced to the following equivalent form, which gives the final value of the static disturbances:

$$(33) m'C_4C' \Sigma N \cos (pnt+X)$$

In the above formula the values of N and X are given by

$$N^2 = (N_a \cos \varphi_a'' - N_b \cos \varphi_b'')$$

$$-N_c \cos \varphi_c'' N_d \cos \varphi_d'')^2 + (N_a \sin \varphi_a'' -$$

$$-N_b \sin \varphi_b'' - N_c \sin \varphi_c'' + N_d \sin \varphi_d'')^2$$

After some rearrangement, the above expression can be put into the form—

$$N^2 = N_a^2 + N_b^2 + N_c^2 N_d^2 - 2N_a N_b \cos (\varphi_a'' - \varphi_b'') - 2N_a N_c \cos (\varphi_a'' - \varphi_c'') + 2N_a N_d \cos (\varphi_a'' - \varphi_d'') + 2N_b N_c \cos (\varphi_b'' - \varphi_c'') - 2N_b N_d \cos (\varphi_b'' - \varphi_d'') - 2N_c N_d \cos (\varphi_c'' - \varphi_d'')$$

As previously discussed, there appears to be no factual evidence to show that, while $\varphi_a'', \varphi_b'', \varphi_c''$ and φ_d'' may take any values, their differences will not be zero, or practically equal to zero. Under these conditions we evidently can write—

$$(34) N = (N_a - N_b) - (N_c - N_d)$$

Under the same simplifying assumptions, we obviously have—

$$(35) \operatorname{tg} X = \operatorname{tg} \varphi$$

where φ is the common value of the phase differences $\varphi_a'' = \varphi_b'' - \varphi_c'' - \varphi_d''$.

We have already shown that N varies as a continuous function of frequency and that, further, if the ratio of the frequency width of the signal

spectrum to the carrier frequency is sufficiently small, then the following relations can be assumed as maximum probable for the range of frequencies included in the "medium" frequency broadcasting range:

$$N_a = .9N_b = .81N_c = .729N_d$$

$$N_b = .9N_c = .81N_d$$

$$N_c = .9N_d$$

10 Hence,

$$N = (N_a - N_b) - (N_c - N_d) = -.1N_b - (-.N_d)$$

$$N = -.1 \times 0.81N_d + .1N_d = +.1 \times .19N_d$$

The ratio r of the "noise" power, with the radio transmitting and receiving system as just described to the "Noise" power which would have been obtained with the standard double side band system of the present art, when the last system is operating at a carrier frequency of $(f_1 + f)$ cycles, is given by—

$$(36) r = \frac{\{(N_a - N_b) - (N_c - N_d)\}^2}{(N_a + N_d)^2} = \frac{.01 \times (.19)^2}{(1.9)^2} = 10^{-4}$$

The above ratio corresponds to a relative reduction of static disturbances equal to, in decibels—

$$r = 10 \log 10^4 = 40 \text{ decibels}$$

The ratio of signal to "noise" power is also improved by the same 40 db., since the signal power of the system above disclosed is equal to that of the double side band system of the present art.

The system just described can be still further improved by the use of 2^{n-1} channels for speech transmission with 2^n channels for noise reception, where n takes the values 1, 2, 3, 4, etc. The equipment costs increase quite rapidly with n , the separation of carrier assignments becomes greater, decreasing thereby the number of available broadcasting stations. Even with the arrangement of Fig. 6 and Fig. 7 of the drawings, the receiving equipment is quite costly, since four duplicate systems of modulators, amplifiers, oscillators, etc., are required. Of course, the improvement indicated of 40 db. may not be required and the simple system first described, shown on Fig. 1, Fig. 2, Fig. 3 and Fig. 4 may prove amply sufficient. There are, however, other radio applications of signal transmission, such as television, wherein the more complex arrangements indicated above may prove invaluable.

In many cases it will be possible to improve the performance of the systems previously described hereinabove by the installation of an adjustable artificial pad P and phase changer Q of the lattice type, as shown on Fig. 8 of the drawings.

Considering the simplest case first—that of the single side band system of Fig. 5, Fig. 2, Fig. 3 and Fig. 4 of the drawings, we will assume that, with the transmitting carrier set at $(f_2 + f_0)$ cycles, the filters H and J of Fig. 3 of the drawings are designed with the following cutoff points:

	Higher	Lower
Filter H	$f_2 + f$	f_2
Filter J	f_2	$f_2 - f$

Under the above assumptions there will be no components of the speech or signal waves in filter J . This is due to the action of band pass filter A of Fig. 5 of the drawings, which allows only waves restricted in their frequency to the band

(f_2+f) to f_2 cycles. The amplitude N_b of the static disturbances flowing through filter J will exceed the corresponding amplitude of the disturbances flowing through filter H, as already shown.

The neutralizing equipment of Fig. 8 of the drawings is inserted between terminals 21-22 and 23-24 of Fig. 4 of the drawings. Since the expression of the static disturbances received over Fig. 3 and Fig. 4 of the drawings is given by Equation 8—

$$(8) \quad m'NC_1C' \Sigma \cos(pnt + X)$$

where—

$$N^2 = N_b^2 - 2N_aN_b \cos(\varphi_b' - \varphi_a'')N^2$$

and $N_a = .9N_b$ as a probable maximum as previously discussed, the installation of the artificial pad P would make it possible to completely balance N_a and N_b as to amplitude, while phase changer Q would eliminate any small difference $(\varphi_b'' - \varphi_a'')$ that may be existing. The pad required would be a 1-db. pad, as so-called in the art, and would reduce the amplitude N_b by about 10%. Hence the new value $N_b' = 0.90N_b = N_a$. On the face of it, this neutralization would completely eliminate static and there would be no reason for any of the more complicated balancing schemes heretofore indicated. This would be the case if the origins or sources of disturbance remained fixed in space as well as in amplitude. To secure complete neutralization with the pad scheme, it would be necessary to have it adjustable and to adjust it more or less continuously, either manually or automatically. The adjustment of the pad P for relative amplitude and that of Q for relative phase will not influence the signal reception since no signals will be flowing through the special equipment of Fig. 8 of the drawings. This is a tremendous advantage.

In the case of the double side band transmission system of the present specifications, the amplitude adjustment has no detrimental effect since the pad P is formed of non-inductive resistances and affects all frequencies alike. The phase adjustment, however, may have to be restricted to definitely small limits of variation with frequency.

All of the systems so far described utilize a band frequency equal in width to that of the signal spectrum or some multiple thereof. It is also possible to secure equivalent effects in static reduction by subdividing or "chopping up" the signal spectrum at the transmitting end, recombining these subdivided sections with their proper phase relations at the receiving end so as not to affect the reception of signals in any way, but neutralizing the static disturbances. In general, the signal spectrum will be divided into 2^n parts, where n is some integer. The subdivision will therefore be carried out into 2, 4, 8, etc., parts, depending upon the value given to the numeric n . The order not to complicate unduly the drawings and the description of the system, we will assume $n=1$. Thus the signal spectrum is divided into just two equal parts. For the same assumption just made, the equipment arrangements required to carry out the purposes of the invention will be given by Fig. 1, Fig. 2, Fig. 3 and Fig. 4 of the drawings, but the design features will be somewhat different from those previously followed, as indicated below.

The supply of carriers C_1 and C_2 on Fig. 1 of 75

the drawings will be made at the frequencies of f_1 and

$$(f_1 + \frac{f}{2})$$

instead of f_1 and (f_1+f) as previously. Band pass filters will also have their cutoff points changed as follows:

10	Cutoff frequencies	
	Higher	Lower
15	$f_1 + \frac{3f}{2}$	$f_1 + f$
15	$f_1 + \frac{f}{2}$	f_1

The signal modulated by carrier C_2 at a frequency of

$$(f_1 + \frac{f}{2})$$

cycles per second will have the usual two side bands. The lower side band will be eliminated by filter A. The upper side band will have frequency components in the range

$$(f_1 + \frac{f}{2})$$

30 and

$$(f_1 + \frac{3f}{2})$$

The portion of the components having the frequency (f_1+f) and

$$(f_1 + \frac{3f}{2})$$

will be passed by filter A. This portion thus transmitted through corresponds to signal waves having the frequency range

$$\frac{f}{2} \text{ to } f$$

We will designate these waves by

$$kCS_2 \cos\left(p_1 + \frac{p}{2} + q_2\right) + \theta$$

where q_2 represents in generic terms 2π multiplied by the frequency of a speech component included in the range

$$\frac{f}{2} \text{ and } f$$

cycles per second.

55 The signal wave modulated by carrier C_1 at a frequency of f_1 cycles will have a lower side band eliminated by filter B and a higher side band which includes components in the frequency range (f_1+f) . The portion of those components having the frequency range

$$f_1 \text{ to } (f_1 + \frac{f}{2})$$

will be passed through by filter B, the remaining portion being strongly attenuated or eliminated.

It would be possible, without departing from the spirit of the specifications, to insert filters in the supply circuit of the signal wave itself, to "chop up" this wave into the two portions

$$0 \text{ to } \frac{f}{2} \text{ and } \frac{f}{2} \text{ to } f \text{ cycles}$$

There appears to be no outstanding advantage in this alternative, and it has not, therefore,

been illustrated to avoid adding unduly to the drawings and specifications. The filters A and B are required anyway to eliminate the lower side band products of the two modulation circuits of Fig. 1 of the drawings.

The modulated wave reaching terminals 7, 8 will be given by the expression—

(37)

$$-kCS_2 \cos \left\{ (p_1 + \frac{p}{2} + q_2)t + \theta \right\} + kCS_4 \{ (p_1 + q_1)t + \theta \}$$

where

$q_1 = 2\pi \times$ frequency of wave included in the band

$$0 \text{ to } \frac{f}{2} \text{ cycles}$$

$q_2 = 2\pi \times$ frequency of waves included in the band

$$\frac{f}{2} \text{ to } f \text{ cycles}$$

S_1 = Amplitude of a component of the signal wave in the range

$$0 \text{ to } \frac{f}{2} \text{ cycles}$$

S_2 = Amplitude of a component of the signal wave in the range

$$\frac{f}{2} \text{ to } f \text{ cycles}$$

f = Width of signal spectrum.

$p = 2\pi \times f$.

The wave given by Equation 37 is amplified and stepped up by the frequency f_0 through the equipment shown on Figure 2 of the drawings. This stepping up of the frequency may be carried in two steps, instead of a single step as shown on the drawings, when and if so required. The wave radiated by the transmitting antenna is given by—

$$(38) \quad -k'CC_3S_2 \cos \left\{ (p_0 + p_1 + \frac{p}{2} + q_2)t + \theta' \right\} + k'CC_3S_4 \cos \{ (p_0 + p_1 + q_1)t + \theta' \}$$

The wave given by Equation 38 is received by the receiving antenna of Fig. 3 of the drawings, amplified by element F to the extent desired and carried through the intermediate frequency demodulation step, using element G of the drawings. The filters H and J are designed with exactly the same cutoff points as filters A and B, respectively. Under the conditions indicated, the waves reaching terminals 15-16 and 17-18 of the drawings will be given by—

$$(39) \quad +ICC_3C_4S_2 \cos \left\{ (p_1 + \frac{p}{2} + q_2)t + \theta_2 \right\}$$

$$(40) \quad +ICC_3C_4S_4 \cos \{ (p_1 + q_1)t + \theta_2 \}$$

The positive sign of Wave 39 is due to the transposition 13, 14-15, 16.

Wave 39 is transmitted through elements K_1 and L_1 of Fig. 4 of the drawings, with the local carrier to element L_1 supplied at a frequency

$$\left(f_1 + \frac{f}{2} \right)$$

cycles. Wave 40 is transmitted through elements K_2 and L_2 of Fig. 4, with the local carrier supply to element L_2 at a frequency of f_1 cycles per second. With the above design features in mind, it will be evident that the signal wave reaching the audio or signal equipment, after transmission through filter M will be given by—

$$(41) \quad l'CC_3C_4C'S_2 \cos (q_2t + \theta_3) + l'CC_3C_4C'S_4 \cos (q_1t + \theta_3)$$

The two terms, in combination, represent the entire signal spectrum originally supplied at the transmitting end, except for the multiplier $l'CC_3C_4C'$. We may therefore express the above in the more compact form—

$$(42) \quad l'CC_3C_4C'S \cos (qt + \theta_3)$$

The low pass filter M, as previously, is designed for the free pass band 0 to f cycles.

We will designate by N the instantaneous value of the intensity of a component of the noise disturbance in the frequency spectrum

$$(f_0 + f_1 + f) \text{ to } \left(f_0 + f_1 + \frac{3f}{2} \right)$$

and by N_b the corresponding intensity of a similar component in the frequency band

$$(f_0 + f_1) \text{ to } \left(f_0 + f_1 + \frac{f}{2} \right)$$

The respective phase differences will be indicated by ϕ_a and ϕ_b . If, as heretofore, we indicate by $(f_0 + f_1 + f + f_n)$ the frequency of the noise component N_a and by $(f_0 + f_1 + f_n)$ that of the component N_b , then the entire noise or static disturbance effect, as finally received in the signal or audio equipment will be given by the summation—

$$(43) \quad m'CC_3C'S \cos (p_n t + X)$$

where

$$N = N_a^2 - 2N_aN_b \cos (\phi_a'' - \phi_b'') + N_b^2$$

and $t g X$ is given by Equation 10.

The important points to remember in connection with the above Formula 43 are—

1. The summation is carried between the frequency intervals

40

$$0 \text{ to } \frac{f}{2}$$

2. The absolute difference in frequency between a component (N_a/f_n) and N_b/f_n is actually f .

In view of Point 2 just made, as previously we can assume that $N_a = 0.90 N_b$. The noise "power," as so-called, which is proportional to the frequency interval included in the summation, is now given by a quantity proportional to

$$\frac{1}{4} (N_b - N_a)^2$$

For the double side band transmission system of the present art, the noise power is proportional to $(N_a + N_b)^2$ or $3.61 N_a^2$. Hence, the ratio of the relative noise "powers" is given by—

$$\frac{1}{4} \frac{(N_a - N_b)^2}{(N_a + N_b)^2} = \frac{1}{4} \frac{.01}{3.61}$$

On the other hand, the signal power is four times as great in the case of the double side system of the present day. Hence, the ratio r of the signal to noise power between the system just described and the double side band system of the present art is given by—

$$(44) \quad r = \frac{4 \times 3.61}{.01} \times \frac{1}{4} = 361$$

Expressed in decibels the improvement obtained can be expressed as—

$$(45) \quad r \text{ (decibels)} = 10 \log 361 = 25.7 \text{ decibels}$$

The above improvement can be further increased by the use of the adjustable pad P and phase changer Q of Fig. 8 of the drawings which

is wired between terminals 21, 22 and 23, 24 of Fig. 4 of the drawings. The operation and performance characteristics of the above neutralizing equipment have already been fully described.

Additional improvement can be obtained, with this method of chopping up the signal at the transmitting end, if the receiving equipment arrangements of Fig. 6 and Fig. 7 are used in the manner outlined below, instead of the arrangements of Fig. 3 and Fig. 4 of the drawings.

At the transmitting end, using Fig. 1 and Fig. 2 of the drawings, the carrier oscillators are set to the following frequencies: C_2 to the frequency

$$(f_1 + \frac{f}{2})$$

and C_1 to the frequency f_1 . The cutoff points of the band pass filters are set, for band pass filter A, to

$$(f_1 + \frac{3f}{2}) \text{ and } (f_1 + f)$$

and for band pass filter B, to

$$(f_1 + \frac{f}{2}) \text{ and } f_1$$

It will be noted that this arrangement at the transmitting end is exactly the same as with the case just previously described. The transmitted wave is therefore given by Equation 38, previously derived.

$$(38) \quad -k'CC_3S_2 \left[\cos(p_0 + p_1 + \frac{p}{2} + q_2)t + \theta' \right] + k'CC_3S_4 \left[\cos(p_0 + p_1 + q_1)t + \theta' \right]$$

At the receiving end, the filters H_1 , H_2 , J_1 and J_2 would be designed on the following basis as to their cutoff points:

	Cutoff frequencies	
	Higher	Lower
H_1	$f_1 + 2f$	$f_1 + \frac{3f}{2}$
H_2	$f_1 + \frac{3f}{2}$	$f_1 + f$
J_1	$f_1 + f$	$f_1 + \frac{f}{2}$
J_2	$f_1 + \frac{f}{2}$	f_1

The components of the first portion of Wave 38, after demodulation by element G of Fig. 6 of the drawings, are included in the frequency band

$$(f_1 + \frac{3f}{2}) \text{ to } (f_1 + f)$$

since q_2 includes the components of the original signal spectrum in the range

$$\frac{f}{2} \text{ to } f$$

Therefore, the first part of the transmitted Wave 38 flows through filter H_2 . The second part of this same Wave 38 has its components in the frequency band

$$(f_1 + \frac{f}{2}) \text{ to } f_1$$

Hence, this second part of Wave 38 flows through filter J_2 .

It follows, as a result of the design methods used, both at the transmitting end and at the receiving end (Fig. 6 of the drawings) that there will be no flow of modulated signal waves through filters H_1 and J_1 .

The modulated signal waves flowing through filter H_2 will be further amplified and demodulated by elements K_2 and L_2 . The waves flowing through filter J_2 will be amplified and demodulated by elements K_4 and L_4 . The four oscillators associated respectively with demodulators L_1 , L_2 , L_3 and L_4 will have carriers supplied at the frequencies

$$(f_1 + \frac{3f}{2}), (f_1 + f), (f_1 + \frac{f}{2}) \text{ and } f_1$$

respectively. The final signal wave will be given, under the above assumed conditions, by—

$$(46) \quad l'CC_3C_4C'S_2 \cos(q_2t + \theta_2) + l'CC_3C_4C'S_1 \cos(q_1t + \theta_1)$$

The sum of the two waves represents exactly the original signal wave, multiplied by the numeric $l'CC_3C_4C'$. The change in sign of the first term of Wave 46 is due to transposition T_3' of Fig. 7 of the drawings. It is clear at once that Equations 43 and 46 are identical and from the standpoint of speech transmission, the receiving arrangements of Fig. 6 and Fig. 7 and those of Fig. 3 and Fig. 4 of the drawings are identical.

There will be static disturbances flowing through all four band filters of Fig. 6 of the drawings. The performance of the equipment shown on Fig. 6 and Fig. 7 of the drawings will be exactly the same as heretofore described in detail, except for the fact that the total frequency band width of the static disturbances received is one-half of that previously assumed. The final static wave received will therefore be given by the summation of Equation 32, with the evident exception that the summation for the variable frequency f_n for the noise is carried out between

$$0 \text{ and } \frac{f}{2}$$

40 instead of 0 and f . The intensity of individual components of the noise wave will be given by Equation 34 with the following changes in the relationships between N_a , N_b , N_c , and N_d .

$$N_a = 0.95 N_b = (0.95)^2 N_c = (0.95)^3 N_d \\ N_b = 0.95 N_c = (0.95)^2 N_d \\ N_c = 0.95 N_d$$

The value of N is therefore given by—

$$N = (N_a - N_b) - (N_c - N_d) = -0.05 N_b + 0.05 N_d \\ N = -0.05 (N_b - N_d) = -0.05 (0.90 - 1.00) N_d \\ N = -0.005 N_d$$

The ratio of the "noise" power with the arrangement of Fig. 6 and Fig. 7 of the drawings, as compared with that previously shown to hold true when the arrangement of Fig. 3 and Fig. 4 of the drawings was considered is given by—

$$60 \quad \frac{(0.005)^2 N_d^2}{(0.019)^2 N_d^2} = \frac{25}{361}$$

The improvement in the ratio of the signal to noise power, with the arrangement of Fig. 6 and Fig. 7 of the drawings, as compared with the arrangement of Fig. 3 and Fig. 4 of the drawings, is given by—

$$70 \quad r = 10 \log \frac{361}{25} = 10(2.557 - 1.398)$$

$$r = 11.60 \text{ decibels}$$

The total relative improvement with respect to the double side band arrangement of the present art is given by $(25.6 + 11.6)$, or 37 db., approximately.

The securing of the above improvement, outstanding in character, is contingent, as well known to those versed in the art, upon the accuracy with which the various elements entering into the amplifiers, demodulators, carrier supplies, etc., can be furnished. It is essential, also, that the carrier supplies, both at the transmitting and receiving ends, be obtained with the same phase. This will require the use of harmonic generation of frequencies. Such a system is described in B. S. Technical Journal October 1937, page 437. Any deficiencies in the above respects can be remedied, at least in part, through the use of the neutralizing equipment of Fig. 8 of the drawings. When the receiving equipment is wired in accordance with Fig. 6 and Fig. 7 of the drawings, it will prove of advantage—one neutralizing equipment of the type shown on Fig. 8 of the drawings between demodulator L_2 and terminals 23, 24, and a second neutralizing equipment of the same type between demodulator L_4 and terminals 27, 28. A third neutralizing equipment, for still finer adjustment, would be wired between terminals 27, 28 and low pass filter M.

Since the adjustments required would be less 1 db. in any case, it is not believed the fidelity of reproduction of the signal will be appreciably affected. If the adjustments made for the neutralizing equipment between L_2 and terminals 23, 24 on one hand and those made in conjunction with the similar equipment between demodulator L_4 and terminals 27, 28 on the other hand are made equal to each other, part of the relatively minor difficulty just referred to would be eliminated. The neutralizing equipment adjustments can be used, as pointed out above, to serve two different purposes. The first purpose would be to insure the theoretically perfect performance of the circuits shown on Fig. 1, Fig. 2, Fig. 6 and Fig. 7 of the drawings. This particular purpose is achieved by fixed adjustments. The second purpose, more difficult of attainment, requires or may require continuously variable adjustments. If this second purpose is achieved, then the improvements obtainable go beyond those indicated herein as practicable to obtain by the theoretically perfect performance of the circuits of Fig. 1, Fig. 2, Fig. 6 and Fig. 7 of the drawings.

A detail account was given in the preceding sections of the present specifications of the means and methods required to secure a substantial reduction in static interference, a primary objective of the present invention. The following additional advantages are inherent in the system disclosed hereinabove, though not specifically claimed.

1. The transmission system disclosed herein is also inherently a system of secret transmission.

2. The receiving system is extremely effective in lowering the internal "noise" level of the receiving set.

Referring to the first of the above points of advantage, it must be apparent immediately that the transmitted wave as given by Equation 2 cannot be received by the standard type double side band radio receiver of today.

Referring to the second point of advantage, it is a well known fact that, in the absence of static interference, whether due to natural or man-made causes, the maximum amplification possible with the receiving set is limited by the "internal" noise level of the receiving set. This noise, in turn, is predominantly associated with the elements of the first tube of the receiving set. Now, in the receiving set, as illustrated on Fig. 3 and

Fig. 4 of the drawings, the first tube marked F is common to the two alternative paths into which the received waves are directed through elements K_1 , L_1 and elements K_2 and L_2 respectively. The internal noise originating in tube F divides itself in equal proportions into the two paths and, in view of the transposition between terminals 13, 14 and 15, 16 in the first path, these two portions mutually cancel each other. The noise in tube F of Fig. 3 of the drawings is given by the expression, in terms of the mean square voltage

$$E_T \cdot E_T^2 = 4k_{TR} f G^2 df$$

For an understanding of the notation used, see "Fluctuation noise in vacuum tubes," Bell System Technical Journal, October 1934, page 643. As brought out in said paper the noise power due to thermal agitation in the grid and plate circuits is distributed equally over all frequencies. It is this last feature and the further point that there exists no difference in attenuation as between the different frequencies of the noise spectrum, in a band 10,000 cycles wide, between the point of origin of the predominant noise (i. e. tube F) and the final audio receiver, that make it possible to eliminate the internal noise more effectively than the static interference.

I claim:

1. In a radio transmitting system, means for modulating the same signal at two different carrier frequencies, means for selecting the upper side bands of the respective modulation products in each case, means for reversing the phase of only one of said side bands, and means for radiating both the reversed and the unreversed side bands.
2. In a radio transmitting system, means for modulating the same signal at two different carrier frequencies, means for selecting the lower side bands of the respective modulation products in each case, means for reversing the phase of only one of said side bands, and means for radiating both the reversed and the unreversed side bands.
3. In a radio transmitting system, means for modulating the same signal at 2^n different carrier frequencies where n is an integer, means for selecting the 2^n upper side bands of the respective modulation products, said side bands constituting a sequence of frequencies of increasing magnitude, means for reversing the phase of every alternate side band, and means for radiating all said upper side bands.
4. In a radio transmitting system, means for modulating the same signal at 2^n different carrier frequencies where n is an integer, means for selecting the 2^n lower side bands of the respective modulation products, said side bands constituting a sequence of frequencies of increasing magnitude, means for reversing the phase of every alternate side band, and means for radiating all said lower side bands.
5. In a radio transmitting system, means for subdividing the original signal spectrum into 2^n parts, where n is some integer, means for modulating each such part separately by a different carrier, means for selecting the 2^n upper side bands of the respective modulation products, said side bands constituting a sequence of frequencies of increasing magnitude, means for reversing the phase of every alternate side band, and means for radiating all said upper side bands.
6. In a radio transmitting system, means for subdividing the original signal spectrum into 2^n parts where n is some integer, means for modu-

lating each such part separately by a different carrier, means for selecting the 2^n lower side bands of the respective modulation products, said side bands constituting a sequence of frequencies of increasing magnitude, means for reversing the phase of every alternate side band, and means for radiating all said lower side bands.

7. In a radio system arranged for single side band receiving, means for separating all incoming waves into two different frequency channels, a carrier supply in each channel means for restricting the useful signal impulses to only one of the above two channels in combination with means for separately demodulating the received waves with carrier supplied in each channel, means for retaining only the lower side band in each channel, and means for reversing the phase of one of the side bands, producing thereby two distinct static waves in phase opposition.

8. In a radio receiving system, the method of reducing static and internal noise which consists in segregating such noise and the received signal impulses into two frequency bands separated by the width of the original signal spectrum, introducing a phase reversal into one of said frequency bands, translating said disturbances into two exactly similar disturbance waves but opposite in phase, covering the same frequency interval, and means for recombining into a single wave, with proper phase relationship, the signal impulses received in said two frequency bands.

9. In a radio receiving system arranged for static and internal disturbance reduction, means for separating incoming waves into two different frequency channels, a separate carrier supply in each channel, means for separately demodulating the received waves with carrier supplied to each channel, means for retaining only the lower side bands of the demodulation products in each channel, and means for reversing the phase of only one of the side bands, thereby producing two distinct disturbance waves in phase opposition.

10. A radio receiving system comprising an antenna, a radio frequency amplifier, an intermediate frequency detector, a source of intermediate frequency carrier supply associated with said detector, band pass filters for segregating the detected waves into two frequency channels, a source of carrier supply in each frequency channel, means for detecting in each said channel with aforesaid carrier supply, means for retaining only the lower side bands of the demodulation products in each channel, means for reversing the phase only of one of said side bands, a common low pass filter and signal responsive means.

11. In a system for the radio transmission of signals, the method of reducing static and internal disturbances at the receiving end which consists in segregating said disturbances into four frequency bands, translating said disturbances into four similar waves, each covering the same frequency band but with the second wave opposing the first, and the fourth wave opposing the third, combining the first and second waves into a single residual wave, combining the third and fourth waves into another residual wave, reversing the phase of one of said residual waves, recombining these residual waves into a single reduced disturbance wave, and restricting the signal impulses into the second and fourth of said frequency bands.

12. In a system for the radio transmission of signals, a radio receiving circuit for the transmitting system specified in claim 1 comprising means for separating incoming waves into two different frequency channels, a separate carrier supply in each channel, means for demodulating the received waves in each said channel, means for retaining only the lower side bands of the demodulation products, and means for reversing the phase of only one of the side bands in cooperative relation with the transmitting system specified in claim 1 for restoring the signal impulses in the two channels in proper phase relationship into a single reinforced signal impulse.

13. In a system for the radio transmission of signals, a radio receiving circuit for the transmitting system specified in claim 2 comprising means for separating incoming waves into two different frequency channels, a separate carrier supply in each channel, means for demodulating the received waves in each said channel, means for retaining only the lower side bands of the demodulation products, and means for reversing the phase of only one of the side bands in cooperative relation with the transmitting system specified in claim 2 for restoring the signal impulses in the two channels in proper phase relationship into a single reinforced signal impulse.

14. In a system for the radio transmission of signals, a receiving circuit for the transmitting system specified in claim 3 comprising means for separating incoming waves into 2^n consecutively numbered different frequency channels, where n is some integer, a carrier supply in each such channel, means for demodulating the received waves by carrier supplied in each channel, means for selecting the lower side bands in each such demodulated wave, means for reversing alternately and in sequence the phase of said side bands, means for recombining all odd numbered side bands into a single channel and all even numbered side bands into another channel, means for reversing the phase of one of said channels and means for recombining both channels in cooperative relation with the transmitting system specified in claim 3 for restricting the signal impulses to the even numbered channels.

15. In a system for the radio transmission of signals, a receiving circuit for the transmitting system specified in claim 4 comprising means for separating incoming waves into 2^n consecutively numbered different frequency channels, where n is some integer, a carrier supply in each such channel, means for demodulating the received waves by carrier supplied in each channel, means for selecting the lower side bands in each such demodulated wave, means for reversing alternately and in sequence the phase of said side bands, means for recombining all odd numbered side bands into a single channel and all even numbered side bands into another channel, means for reversing the phase of one of said channels and means for recombining both channels in cooperative relation with the transmitting system specified in claim 4 for restricting the signal impulses to the even numbered channels.

16. In a radio transmitting circuit comprising means for modulating the same signal by two carriers adjacent in frequency, means for selecting the upper side bands of the modulation products, means for suppressing both carriers and the lower side bands, means for reversing the phase of only one of the retained side bands in

combination with means for radiating both of said retained side bands.

17. In a radio transmitting circuit comprising means for modulating the same signal by two carriers separated in frequency by the width of the signal spectrum, means for selecting the upper side bands of the modulation products, means for suppressing both carriers and the lower side bands, means for reversing the phase of only one of the retained side bands in combination with means for radiating both of said retained side bands.

18. In a radio transmitting circuit comprising means for modulating the same signal by two carriers adjacent in frequency, means for selecting the lower side bands of the modulation products, means for suppressing both carriers and the upper side bands, means for reversing the phase of only one of the retained side bands in combination with means for radiating both of said retained side bands.

19. In a radio transmitting circuit comprising means for modulating the same signal by two carriers separated in frequency by the width of the signal spectrum, means for selecting the lower side bands of the modulation products, means for suppressing both carriers and the upper side bands, means for reversing the phase of only one of the retained side bands in combination with means for radiating both of said retained side bands.

20. In a radio transmitting system, means for modulating the same signal at 2^n different carrier frequencies where n is some integer, means for selecting the upper side bands of the respective modulation products, means for reversing alternately and in sequence the phase of said side bands, means for combining adjacent channels by sub-groups of two into 2^{n-1} channels, means for reversing alternately and in sequence the phase of said 2^{n-1} channels, means for repeating the procedure of phase reversal and progressive reduction in number of channels until all 2^n channels are reduced in number to a single final channel and means for radiating all side bands of the upper type in said final channel.

21. In a radio transmitting system, means for modulating the same signal at 2^n different carrier frequencies where n is some integer, means for selecting the lower side bands of the respec-

tive modulation products, means for reversing alternately and in sequence the phase of said side bands, means for combining adjacent channels by sub-groups of two into 2^{n-1} channels, means for reversing alternately and in sequence the phase of said 2^{n-1} channels, means for repeating the procedure of phase reversal and progressive reduction in number of channels until all 2^n channels are reduced in number to a single final channel and means for radiating all side bands of the lower type in said final channel.

22. In a system for the transmission of radio signals, a radio receiving circuit comprising means for separating incoming waves into 2^n different frequency channels where n is some integer, a separate carrier supply in each channel, means for demodulating the received waves in each channel, means for selecting the lower side bands of each such demodulated wave, means for reversing alternately and in sequence the phase of said side bands, means for combining adjacent channels by sub-groups of two into 2^{n-1} channels, means for repeating the procedure of phase reversal and progressive reduction in number of channels until all 2^n channels are reduced in number to a single final channel in cooperative relation with the transmitting system of claim 20 as to the phase reversals of the different frequency channels for reinforcing the signal impulses received.

23. In a system for the transmission of radio signals, a radio receiving circuit comprising means for separating incoming waves into 2^n different frequency channels where n is some integer, a separate carrier supply in each channel, means for demodulating the received waves in each channel, means for selecting the lower side bands of each such demodulated wave, means for reversing alternately and in sequence the phase of said side bands, means for combining adjacent channels by sub-groups of two into 2^{n-1} channels, means for repeating the procedure of phase reversal and progressive reduction in number of channels until all 2^n channels are reduced in number to a single final channel in cooperative relation with the transmitting system of claim 21 as to the phase reversals of the different frequency channels for reinforcing the signal impulses received.
